HAIR EXTRACTING DEVICE

Harry Orner, Cleveland Heights, Ohio, assignor
of one-half to William Isler, Cleveland Heights,
Ohio

Application August 6, 1946, Serial No. 688,777

17 Claims. (Cl. 128—355)

1

This invention relates, as indicated, to a hair extracting device, but has reference more particularly to improvements in the devices which form the subject matter of my copending patent application, Serial No. 561,565, now Patent No. 2,413,576 and Patent No. 2,400,227, granted to Julius Fichter.

The hair extracting device described in the aforesaid patent to Fichter is stated to embody various improvements in the device described in the aforesaid patent application, but is nevertheless characterized by various objectionable features, among which the following may be enumerated:

(a) Hair, parts of skin and other foreign matter tend to accumulate between the end of the sleeve and the face of the head of the shaft, thereby eventually interfering sufficiently with the movement of the sleeve toward the head to prevent the hair from being clasped or gripped between the sleeve and head.

(b) The sudden application of rotary force to the hair being extracted, due to the fact that both the sleeve and the shaft are directly power-driven, results in breaking of the hair above its juncture with the skin, leaving stubs of hair in the skin. These stubs of hair present an objectionable appearance of dots corresponding in color to the color of the hair. Moreover, these stubs are so short that they cannot be extracted until they have grown so sufficient length to permit them to be clasped between the end of the sleeve and the face of the head of the shaft. In other words, the sudden application of the aforesaid rotary force on the hair which is clasped by the device tends to very suddenly remove the slack in the hair, and tends to break the hair, in a manner analogous to that in which a slack fishline is broken under sudden pull.

(c) The device is formed of an excessively large number of parts, a great many of which are unnecessary, and others of which are of complicated construction as well as difficult to manufacture and assemble.

It is a primary object of the present invention to provide a hair extracting device of the type described, but which obviates all of the aforesaid difficulties and disadvantages.

More specifically, it is an object of the present invention to provide a hair extracting device which has incorporated therein means for automatically maintaining the space between the sleeve and head of the shaft clean and clear of hair, parts of skin and other foreign matter. The device, in other words, is self-cleaning.

2

Another object of the invention is to provide a device of the character described, the use of which reduces to a minimum such breakage of the hair as has been hereinbefore described.

A further object of the invention is to provide a device of the character described, which consists of a minimum number of parts which are of simple construction, relatively easy to manufacture and assemble, and which, as a whole, is long lasting, trouble-proof, and inexpensive to operate.

A still further object of the invention is to provide a device of the character described which removes hair in an extremely efficient manner.

Other objects and advantages of the invention will be apparent during the course of the following description.

In the accompanying drawings, forming a part of this specification, and in which like numerals are employed to designate like parts throughout the same.

Fig. 1 is a longitudinal cross-sectional view of a hair extracting device embodying my invention;

Figs. 2, 3, 4 and 5 are cross-sectional views, taken on the lines 2—2, 3—3, 4—4 and 5—5, respectively, of Fig. 1;

Fig. 6 is an end elevational view of the device, as viewed in the direction indicated by the line 6—6 of Fig. 1;

Fig. 7 is a fragmentary elevational view, on an enlarged scale, of the right end portion of the device shown in Fig. 1;

Fig. 8 is a view similar to Fig. 7, but with the sleeve in its operative or hair-clasping position, 180 degrees from the position shown in Fig. 7, and

Fig. 9 is a cross-sectional view, taken on the line 9—9 of Fig. 8.

Referring more particularly to the drawings, the device will be seen to comprise a one-piece handle 1, having a bore 2 therein, which is counterbored as at 3 to provide a seat or shoulder 4.

Disposed within the counterbore 3 of the handle is a tubular sleeve 5, which extends substantially the length of the handle 1, and one end 6 of which projects from the handle, the sleeve being journaled within the handle and being freely rotatable within the latter, without benefit of bearings of other anti-friction devices. The sleeve 5 is provided at one end with open-ended longitudinally-extending slots 7 and 8, which are disposed diametrically opposite each other, and which serve a purpose to be presently described. The other end of the sleeve 5 is provided with a substantially semi-annular

thrust surface 9, and a second substantially semi-annular surface 10, the plane of which is offset rearwardly from the plane of the surface 9. The surfaces 9 and 10 are interconnected at their ends by inclined surfaces or ledges 11 and 12, which constitute cams.

Disposed within the sleeve 5 of the device is a shaft 13, the major portion of which is hollowed out, as at 14, to decrease the weight thereof. The shaft 13 is of slightly smaller external diameter than the internal diameter of the sleeve 5, and is provided, adjacent its ends with portions 15 and 16 of enlarged external diameter, forming bearing surfaces by which the shaft is supported in the sleeve.

The shaft 13 is further formed to provide a head 17 having an annular face 18 which is adapted to cooperate with the surface 9 of the sleeve to grip or clasp hair and remove the latter.

The shaft 13 has threadedly secured to the rear end thereof a shaft 19 having a head 20 at its rear end. Disposed about the shaft 19 is a pair of spaced thrust members or washers 21 and 22, between which a compression coil spring 23 is interposed. The washers 21 and 22 are provided at diametrically opposite points of each with tenons 24 which extend into the slots 7 and 8. The spring 23 exerts a force tending, on the one hand, to move the sleeve 5 to the right, as viewed in Fig. 1, and on the other hand, to move the shaft 13 to the left, so that there is a constantly acting resilient force tending to move the surfaces 9 and 18 into contact with each other to perform the hair extracting function to which reference has been made.

The sleeve 5 is adapted to be positively and directly driven by a driving member 25 which is journaled in the bore 2 of the handle. The member 25 has a forward portion 26 which extends into the rear end of the sleeve 5 and is provided with a pin 27 extending diametrically therethrough, and the ends of which extend into the slots 7 and 8 of the sleeve, so that when the member 26 is driven as by threadedly connecting a power-driven flexible shaft (not shown) thereto, the sleeve will be driven. The member 25 is also provided with an annular recess 28 in which a snap ring 29 is mounted. The member 25 is free to move slightly in an axial direction in the bore 2, but is prevented from moving out of the bore by reason of the engagement of the ring 29 with the shoulder 4 of the handle, and from moving too far to the right by reason of the engagement of said ring with the end of the sleeve 5.

For the purpose of intermittently retracting the sleeve 5 as the latter is rotated, in order to free or release the hair which has been clasped between the surface 9 and 18, I have provided a member 30, which is secured to the forward portion of the handle 1 as by rivets or screws 31. The member 30 extends forwardly of the handle and has a downwardly or radially-inwardly extending portion 32, which extends into the space between the enlarged portion 16 of the shaft 13 and the surface 18 of the head 17, being of a thickness corresponding with the length of this space. The lower end of the portion 32 of the member 30 embraces the shaft 13 and is formed to provide chisel or wiper edges 33 and 34 which bear against the shaft 13.

The operation of the device will be readily understood from the foregoing description, but may be briefly described as follows:

The driving member 25 is adapted to be ro-

tated by means of a power-driven flexible shaft, and, through the pin 27, transmits its rotary movement to the sleeve 5. As the sleeve 5 is rotated, it is also reciprocated so as to intermittently cause the surface 9 of the sleeve to come into engagement with the face 18 of the head 17 of the shaft 13, and at such time, hair may be gripped or clasped by such surfaces. The movement of the surface 9 of the sleeve toward the face 18 of the head 17 is effected automatically due to the action of the spring 23. Movement of the surface 9 away from the surface 18 for the purpose of releasing the hair which has been thus gripped or clasped is effected by the portion 32 of the member 30. As the sleeve 5 rotates in a counterclockwise direction, as viewed in Fig. 9, the portion 34 of the member 30 comes into engagement with the inclined cam surface 11 of the sleeve, causing the sleeve to be retracted to the position shown in Fig. 7, and the sleeve is maintained in such retracted position for approximately one-half of the revolution of the sleeve, corresponding to movement of the sleeve through the arc indicated between the arrows 25 in Fig. 9, which arc is equivalent in length to the arc of the surface 9.

The aforesaid arc also corresponds to the portion of the device which is to be applied to the skin for the purpose of extracting hair, and in order to avoid placement against the skin of that portion of the device which is not effective to remove hair, the member 30 may be provided with a guard indicated by the broken lines 35 in Fig. 9 which extends over the ineffective portion of the space between the sleeve and head.

In the event that the sleeve 5 is rotated in a clockwise direction, as viewed in Fig. 9, the portion 32 of the member 30 comes into engagement with the inclined cam surface 12 of the sleeve, causing the sleeve to be retracted to the position shown in Fig. 7. The effective portion of the device, in that case, is at the opposite side of the device from that shown in Fig. 9, and in such event, a guard disposed at the opposite side of the device from that shown in Fig. 9 is to be employed.

In order to insure that the surface 9 will come into contact with the surface 18 and will not be obstructed from so doing by the portion 32 of the member 30, the distance between the offset parallel planes of the surfaces 9 and 10, is, as clearly shown in Fig. 8, slightly greater than the thickness of the said portion 32 of the member 30.

55 The member 30 performs a dual function. Its primary function has already been described. It also functions to strip or remove hair, skin and other foreign matter which might otherwise accumulate between the sleeve and head of the device. For this purpose, the sharp edges 33 and 34 are effective to strip from the shaft 13 hair or other matter which adheres to the shaft. At the same time, the rear edges of the portion 32 of the member 30 are effective to remove hair and other matter which adheres to the surfaces 9, 10, 11 and 12 of the sleeve, and the front edges of the portion 32 of the member 30 are effective to remove hair and other matter which adheres to the face 18 of the head 17.

70 It will be noted that the shaft 13 is not positively rotated, but is free to rotate independently of the sleeve, rotary movement being indirectly transmitted to the sleeve by the shaft through the medium of the hair which is being extracted. This permits a slight slipping of the

5

hair just prior to the clasping of the hair between the sleeve and head of the device, which, in turn, permits the hair to straighten out prior to its being fully clasped and removed from the skin. This prevents breaking of the hair above its junction with the skin, and thereby avoids leaving stubs of hair in the skin.

It will be further noted that the device consists of a minimum number of parts which are of simple construction, relatively easy to manufacture and assemble, and which, as a whole, is long lasting, trouble-proof and inexpensive to operate. In particular, it may be noted that there is no end thrust on any of the internal parts of the device, since all such end thrust is taken up by the member 30 between the end of the sleeve and the head of the shaft. Moreover, no means is required to drive the shaft, and the sleeve and shaft can be assembled as a separate unit outside of the handle and then inserted into the handle and maintained in position by the member 30. Secondary manufacturing operations, such as drilling, slotting and threading are thus reduced to a minimum.

It is to be understood that the form of my invention, herein described, is to be taken as a preferred example of the same, and that various changes may be resorted to without departing from the spirit of my invention, or the scope of the subjoined claims.

Having thus described my invention, I claim:

1. In a device of the character described, the combination of a handle, a sleeve rotatably mounted in said handle for reciprocating movement, means for driving said sleeve, a shaft journalled in said sleeve and rotatable independently of said sleeve, one end of said sleeve projecting from said handle and having an arcuate end surface, said shaft having a head projecting from said sleeve the inner face of which abuts the end surface of the sleeve to form opposed hair gripping surfaces, and a member mounted externally of said handle and engaging said sleeve to intermittently retract said sleeve from said head as the sleeve is rotated.

2. A combination, as defined in claim 1, wherein said member is interposed between said hair gripping surfaces and has wiping engagement therewith whereby to strip from said sleeve and shaft any hair or other matter which adheres to the sleeve and shaft.

3. In a device of the character described, the combination of a handle, a tubular sleeve mounted for reciprocable movement within said handle, means for positively rotating said sleeve, a shaft journalled in said sleeve and rotatable independently of said sleeve, and means for reciprocating said sleeve, said sleeve and shaft having portions cooperable to remove hair from the skin as the sleeve is rotated.

4. In a device of the character described, the combination of a handle, a tubular sleeve mounted for reciprocable movement within said handle, means for positively rotating said sleeve, a shaft journalled in said sleeve and rotatable independently of said sleeve, and means for reciprocating said sleeve, said means comprising a spring effective to move said sleeve in one direction and a camming member mounted on said handle and effective to move said sleeve in the opposite direction, said sleeve and shaft having portions cooperable to remove hair from the skin as the sleeve is rotated.

5. In a hair extracting device of the character described, the combination of a handle hav-

6

ing a longitudinal bore therein, a sleeve member journalled in the bore of said handle, a shaft journalled in said sleeve member, said shaft having an annular surface formed thereon overlying one end of said sleeve member, said annular surface and said end of said sleeve member forming opposed hair gripping surfaces, spring means disposed between said shaft and said sleeve member for resiliently maintaining said hair gripping surfaces in abutment, a retainer member secured to said handle and engaging said shaft for maintaining said shaft against longitudinal displacement relatively to said handle, and cam surfaces provided on said end of said sleeve member for engagement with said retainer member to effect reciprocation of said sleeve member in response to rotation thereof.

6. A combination, as defined in claim 5, in which said retainer member projects into an annular recess formed on said shaft.

7. A combination, as defined in claim 6, in which said retainer member has scraper edges provided thereon for wiping engagement with said hair gripping surfaces.

8. In a hair extracting device of the character described, the combination of a handle having a longitudinal bore therein, a sleeve member journalled in the bore of said handle, a shaft journalled in the bore of said sleeve member, said shaft having an annular surface abutting one end of said sleeve member, said annular surface and said end of said sleeve member forming opposed hair gripping surfaces, cam means associated with said sleeve member for intermittently retracting said sleeve member to hair releasing position relatively to said shaft in response to rotation of said sleeve member, and a scraper element secured to said handle and engaging said hair gripping surfaces when said sleeve member is in retracted position, whereby to cleanse said hair gripping surfaces.

9. A combination, as defined in claim 8, in which cam surfaces are provided on said end of said sleeve member and said scraper element operatively engages said cam surfaces to effect said intermittent retraction.

10. In a device of the character described, a handle having a longitudinal bore therein, a sleeve member journalled in the bore of said handle, a shaft member mounted in the bore of said sleeve member, said shaft member having an annular end portion abutting one end of said sleeve member whereby to form opposed hair gripping surfaces, means for rotating one of said members, cam means provided on one of said members for effecting intermittent retraction of said member relatively to said other member in response to said rotation, and means secured to said handle in wiping engagement with said hair gripping surfaces when said one member is in retracted position.

11. A combination, as defined in claim 10, in which said last named means comprises a scraper blade projecting radially into the rotary path of movement of said hair gripping surfaces.

12. A combination, as defined in claim 10, in which cam surfaces are provided on said sleeve member for operative engagement with said last named means.

13. A combination, as defined in claim 12, in which said last named means comprise a cam follower projecting radially into the rotary path of movement of said hair gripping surfaces.

14. In a device of the character described,

the combination of a handle, a sleeve member slidably journaled in said handle, a shaft member journaled in said sleeve member, said members having annular end portions cooperating to form hair gripping surfaces, spring means yieldably maintaining said annular portions in abutment, means responsive to rotation of said sleeve member for reciprocating said sleeve member relatively to said shaft member to cause said hair gripping surfaces to move toward and away from each other, and driving means connected to said sleeve member for effecting positive rotation thereof, said rotation being transmitted to said shaft member upon abutment of said hair gripping surfaces.

15. In a hair extracting device of the character described, the combination of a handle, a tubular sleeve rotatably mounted within said handle for reciprocable movement therein, drive means engaging said sleeve to effect rotation thereof, a hair gripping member overlying the end of said sleeve and rotatable relatively thereto and independently thereof, said member having an annular hair gripping surface abutting the end of said sleeve whereby to clamp hair therebetween, resilient means engaging said sleeve to yieldably maintain said hair gripping surfaces in abutment, and cam means engaging said sleeve to effect reciprocation thereof in response to rotation thereof.

20. A combination as defined in claim 15 wherein a scraping element is secured to said handle and interposed between said hair gripping surfaces for intermittent wiping engagement therewith.

25. In a hair extracting device of the character described, a handle, a tubular sleeve rotatably mounted in said handle and longitudi-

nally slidable therein, drive means engaging said sleeve to effect rotation thereof, said sleeve having one end thereof projecting from said handle, an annular cam surface provided on the exposed end of said sleeve comprising an elevated portion of said end surface, a rotatable annular hair gripping member overlying said exposed end of said sleeve in abutment with said elevated portion of said end surface of said sleeve, whereby to clamp a hair therebetween, spring means engaging said sleeve and yieldably maintaining said sleeve in abutment with said hair gripping member, and a retaining element secured to said handle and engaging said hair gripping member to secure said member against longitudinal movement relatively to said handle, said retaining element having a portion thereof interposed between said member and the non-elevated portion of said end surface whereby to separate said hair clamping surfaces in response to rotation of said sleeve.
